Patented Jan. 3, 1928.

UNITED STATES PATENT OFFICE.

JAY ALBERT STOUGH, OF TULSA, OKLAHOMA.

TANK ROOF.

Application filed October 8, 1925. Serial No. 61,350.

My invention relates to tank roofs and more particularly to a roof for oil storage tanks, the principal object of the invention being to provide a practically vapor-tight roof whereby liability of ignition of oil vapors from static sparks will be eliminated or reduced to a minimum.

In accomplishing this object I have provided improved details of structure, the preferred forms of which are illustrated in the accompanying drawing wherein the single figure is a fragmentary perspective view of a tank provided with a roof constructed according to my invention. Referring more in detail to the drawing by numerals of reference:—

The tank 1 may, except as hereinafter noted, be of the ordinary type used on tank farms for storing large quantities of crude petroleum, and consisting of the usual uprights 2 for supporting beams 3 on which the roof rafters 4 rest, the rafters 4 carrying sheathing 5 covering the top of the tank; the side walls 6 being of usual metallic construction, having an angle 7 at its upper end.

In my preferred form of roof the sheathing 5 is preferably covered with a layer of roofing paper 9, which is covered with an adhesive coat (preferably sodium silicate) to which a second layer of paper 10 is applied, and mopped with a coat of fibrous cement. Then a layer of fibrous insulation 11, preferably about one-half inch in thickness, is laid over the last layer of paper. These layers of paper and sodium silicate tend to make the roof gas-tight and insulate the contents of the tank from heat transmission through the roof.

The insulation is then mopped with a coat of fibrous cement and the entire roof covered, preferably to within a short distance of its eaves with ordinary two or three ply asbestos or felt roofing 12.

In order to equip the roof with the usual gauge hole and other fittings, and to make an efficient connection between the top of the wall 6 and the roofing 12, as well as to provide a lightning arrester, I provide at the edge of the roof a metallic circular ring 13, comprising a plurality of segments or members 14 arranged in circular series, the adjacent edges overlapping as at 15 and secured together by bolts or other fastening devices 16.

The outer edges of the segments are secured to the horizontal flange 17 of the wall

angle 7 by bolts 18, there being a gasket 19 inserted between the angle 7 and the edges of the segments to make the joint gas-tight, the inner edges of the segments overlapping 60 the edge 20 of the roofing 12 and secured in place by lag screws 21 which extend through openings in the edge of the plates and through the roofing, into the sheathing boards. The inner edges of the segments are sealed by flexible cement 22 which extends between the overlapping edges of the segments on the roofing and is spread on an incline from the surface of the roofing flush with the surface of the segments.

The fittings for the tank, such as the gauge hole cover 23, flanged pipe couplings 24 and the like, are secured to the metallic ring in their proper positions by bolts 24' or the like which extend through a flange 25 on the fitting and through the ring segments and are drawn up tight to make a firm contact between the metal surfaces.

By providing the metallic ring to carry the fittings and make connection between the wall of the tank and the roofing 12, and with the use of the flexible cement as described, liability of seams opening up due to the expansion and contraction of the tank, will be eliminated and the highly volatile 85 gases in the tank cannot become ignited by static discharge, since the parts are all firmly connected to the metallic ring and the ring securely bolted to the wall of the tank so that any static will necessarily be grounded 90 through the wall of the tank.

What I claim and desire to secure by Letters-Patent is:—

1. A tank comprising a side wall and roof sheathing, an angle member at the upper 95 edge of the wall, a cover of insulating material on the sheathing, sheeting on said cover, a metallic ring overlying the angle member at its outer edge and intermediately engaged with said cover and overlying the 100 sheeting at its inner edge, sealing material between the outer edge of the ring and the angle member and between the inner edge of the ring and said sheeting, and means for securing the ring to the angle member and 105 to the roof sheathing.

2. A tank comprising a side wall and roof sheathing, an angle member at the upper edge of the wall, sheeting on the roof sheathing, a metallic ring overlying the angle 110 member at its outer edge and overlying the roof sheeting at its inner edge, compress-

- ible sealing material between the outer edge of the ring and the angle member and between the inner edge of the ring and the roof sheeting, said sealing material being extended to cover adjacent ring edge and sheeting portion to provide an exterior annular seal, and means for securing the ring to the angle member and to the roof sheathing.
- 10 3. A tank comprising a side wall and roof sheathing, an angle member at the upper edge of the wall, a cover of insulating material on the roof sheathing, sheeting on said cover terminating short of the edge of the roof, a metallic ring overlying the roof sheeting at its inner edge and overlying the angle member at its outer edge and intermediately engaged with said insulating material, with the edge of the ring terminating flush with the edge of the angle member.
4. A tank comprising a side wall and roof sheathing, an angle member at the upper edge of the wall, sheeting on the roof sheathing terminating short of the edge of the roof, a metallic ring overlying the angle member at its outer edge and overlying the edge of the sheeting at its inner edge, sealing material between the outer edge of the ring and angle member and between the inner edge of the ring and the sheeting, and means for securing the ring to the angle member and to the roof of the tank.

In testimony whereof I affix my signature.

JAY ALBERT STOUGH.
